UNITED STATES PATENT OFFICE.

MORRIS PAUL KIRK, OF SALT LAKE CITY, UTAH, ASSIGNOR OF ONE-HALF TO JOHN H. LEAVELL, OF SALT LAKE CITY, UTAH.

HYDRAULIC CLASSIFIER.

1,102,672.

Specification of Letters Patent.

Patented July 7, 1914.

Application filed August 4, 1913. Serial No. 782,838.

To all whom it may concern:

Be it known that I, MORRIS P. KIRK, a citizen of the United States, residing at Salt Lake City, in the county of Salt Lake and State of Utah, have invented certain new and useful Improvements in Hydraulic Classifiers, of which the following is a specification.

This invention relates to a certain new and useful improvement in that type of apparatus commonly known as hydraulic classifiers.

In the preparation of finely crushed pulps in ore concentrators and the allied industries, it is necessary to separate and subdivide the pulp into different sizes or classes previous to the separation on the concentrating or finishing machines. In the type of invention referred to, the separation and subdivision of the pulp has been accomplished by subjecting the pulp as a whole, to a rising column of water in which the heavier and larger particles fall and the lighter or smaller particles are caused to ascend. By regulating the velocity of this rising column of water, various sizes or classes of pulp result and this has been accomplished by a variety of means from time to time.

My present invention comprehends an improved means for accomplishing the sizing or classification of the ore particles whereby the operations may be more perfectly and accurately performed and a higher recovery of the valuable contents of the concentrating or finishing means to which the particles are fed, may be obtained.

With the above and other objects in view, my invention consists of the parts and the constructions, arrangements and combinations of parts which I will hereinafter describe and claim.

In the accompanying drawings forming part of this specification and in which similar reference characters indicate like parts in the several views;—Figure 1 is a vertical longitudinal section of a hydraulic classifier embodying the salient features of my invention. Fig. 2 is a top plan view of the same. Fig. 3 is a cross sectional view on the line X—X of Fig. 1. Fig. 4 is an enlarged detail in vertical section of one of the spigots or castings on the lower end of the sorting

column. Fig. 5 is a cross section of the same. Fig. 6 is an enlarged detail showing the spiral grooves on the lower end of one of the stand pipes, H.

In said drawings, A, represents the main tank or box which may have greater length than width and which has a sloping bottom, said tank or box being, preferably, of uniform width throughout, and of varying depth, but it will be understood that I do not limit myself to this particular design of tank, as said tank may be wider at the discharge end than at the receiving end and it may have a uniform depth if preferred, said tank or box having internal cross partitions, a, forming in the lower portion of the tank a number of downwardly converging compartments, b, of different sizes, as is well known in this art. The tank is provided with a series of sizing or sorting columns, B', B², B³, B⁴, B⁵ and B⁶, of which there may be any desired number, according to the size and capacity of the tank, and the number of the compartments, b, thereof, each of the sorting columns comprising a vertical member or stand-pipe, H, to the top of which is fitted an air-tight cap, H'; the bottom of the pipe, H, is provided with a series of spiral grooves, J, as shown particularly in Fig. 6, and one of the said pipes extends through the bottom or conical end of each of the downwardly diverging compartments, b, formed in the tank, as shown.

The stand pipe, H, extends a substantial distance into the tank and the purpose of this is to facilitate the reaching down to remove the pipe in case of clogging. It also should be of sufficient length to provide an air space inside of the pipe, which acts as a sort of governor, in utilizing the momentary fluctuations which occur in water pressure. This long pipe also serves to retard the current in the classifier tank and to bring the particles to be separated down into the sorting chambers, as said particles travel along from the intake to the discharge of the tank. I have conducted a great many experiments with regard to this pipe and why the air cushion should effect the pressure I have not been able to figure out scientifically, but it does so nevertheless. Surrounding the member or pipe, H, is a pipe, G, of larger diameter

ter than said pipe, H, so as to form an intervening annular chamber, c, said pipe, G, being threaded into engagement with a flange, d, which is secured over the bottom opening 5 of the compartment with which the pipe connects. The lower end of the pipe, G, is threaded into engagement with a casting, E, which I will hereinafter refer to as a spigot, and which casting is formed with double 10 walls, F—F', with an intervening annular space, e, which connects with the space, c, between the stand-pipe, H, and the pipe, G, before mentioned. One of the castings or spigots is provided for each of the stand 15 pipes, H, and each of said castings or spigots has a lateral outlet through which water under pressure may be furnished, and the bottom of the spigot has a clean-out opening to receive a suitable plug, L.

20 In the type of apparatus shown for illustrative purposes the sorting columns are of different size and the compartments which the stand-pipes of these columns enter are also of different size, the purpose of which 25 will be hereinafter described. The apparatus shown is provided with means for making separate classifications, with a rejection, or overflow at the point, C, and any desired number of classifications may be 30 made without departing from the salient features of the invention.

As before described, each of the several spigots, B', B², &c., is provided with water under pressure and which is admitted 35 through the side opening, h, below the lower end of the stand-pipe.

In the investigations and experiments leading up to my invention, it was discovered that for close and accurate classification, a whirling or circular motion to the 40 water in the rising column was essential. With pulp consisting of all sizes from comparatively coarse particles down to infinitely fine or small portions, this whirling action 45 was necessary to separate the one from the other, the finer particles having a tendency to attach themselves to the larger ones, but by giving the pulp a whirling motion the particles are separated from one another by the 50 action of the centrifugal forces set up. It was further found that, when whirling the water in the sorting column formed by the pipe, G, in the absence of the vertical pipe, H, a vortex was formed which produced a 55 countercurrent that had the effect of returning the particles downward, and so kept them in constant circulation very much the same way as the familiar whirling of chips in a whirlpool, but by introducing the vertical stand-pipe, H, within the pipe or 60 column, G, the vortex was broken up and the column became an ascending one at the same time having a circular motion.

My invention is, therefore, the result of 65 the investigations and discoveries mentioned,

and in order to produce the desired whirling effect to the column, I provide the lower end of the member or pipe, H, with spirally-arranged grooves, J, as shown in Fig. 6, whereby the fluid under pressure, enters the 70 inlet, k, in the spigot or casting, E, and is distributed into the chamber bounded by the inner walls, F, F', and the lower spirally grooved end of the pipe, H, and it thence passes through the grooves and ascends the 75 annular chamber, c, formed between the concentric spaced pipes, G, H. As before stated, the purpose and effect of the grooves J, is to impart a whirling motion to the water as it ascends. Particles of ore heavy 80 and large enough to resist the velocity of the rising water fall through the space, c, and are finally discharged through a bottom opening controlled by the spigot plug, L; the lighter or smaller particles, unable to resist the force of the water, ascend and pass on to the next compartment of the tank in which compartment a similar operation is performed. In other words, the described 85 operation of the single sorting column, as well as the construction of the spigot thereof, is the same in each of the various compartments of the tank, the particles heavy enough to resist the velocity of the water settling into one of the spigots and the particles too light 90 pass on to the next and so on, through the whole series of spigots. The first spigot, B', that is, the one next to the inlet end of the tank, therefore, discharges the coarser particles, the next succeeding spigot discharges 95 the next smaller particles, and so on in rotation to the final spigot, B⁶, the finest of all, together with the accumulated water being discharged at the overflow point, C, at the upper tail end of the tank.

100 It will be understood, of course, that the proportions of the different parts will vary according to the tonnage to be handled and the nature and composition of the material to be treated. For instance, on the first 105 spigot, B', which is shown as of comparatively small size and which will be adjusted to a comparatively high velocity, and will discharge the coarsest of the particles, the spiral may consist of four grooves only, whereas in the spigot, B⁶, where the amount of rising water is small and the diameter or size of the compartment with which this spigot communicates is comparatively large, 110 as many as twelve or more spirals for the proper subdivision of the water may be provided. The pitch or number of convolutions may also be varied to suit each particular requirement and the shape also of these 115 grooves may be varied and adjusted within wide limitations, the essential principles, however, remaining the same, viz: a truly rising column within an annular space, having a circular or whirling action, for the 120 purposes before described.

Having thus described my invention what I claim as new and desire to secure by Letters Patent is:—

1. In a hydraulic classifier, a sorting column comprising concentric spaced members between which the fluid ascends, and a member at the lower end of the column having fluid channels inclined between the horizontal and vertical and opening upwardly directly into the base of the column and adapted to impart a circular or whirling action to the fluid at the point where it discharges from the channels.
2. In a hydraulic classifier, the combination with a tank, of a sorting column communicating with the base of said tank and comprising concentric spaced members between which the fluid ascends, one of said members being longer than the other and extending a substantial distance up into the tank and above the discharge of the latter into the sorting column, and a member at the lower end of the column having fluid channels inclined between the horizontal and vertical and opening upwardly directly into the base of said column, and adapted to impart a circular or whirling action to the fluid at the point where it discharges from the channels into said column.
3. In a hydraulic classifier, the combination with a tank, of a sorting column communicating with the base thereof, means for producing whirling currents in the column, said column including a centrally-disposed pipe which extends a substantial distance up into the tank and above the discharge of the latter into the sorting column.
4. In a hydraulic classifier, a sorting column comprising tubular members arranged one within the other, one of said members extending a substantial distance above the other and above the inlet thereto, and having means for producing whirling currents in said column.
5. In a hydraulic classifier, a sorting column comprising a pipe, a spigot on the lower end thereof having double spaced walls and an internal chamber bounded by the innermost of said walls, and a pipe within said first-named pipe and extending above the same, and spaced therefrom to form an intervening chamber in which the column of fluid ascends, said second-named pipe being fitted to the upper end of said internal chamber and provided with a spirally grooved lower end, means for admitting water to said internal chamber below the spirally grooved end of said pipe, whereby the spiral grooves induce a circular or whirling action to the fluid as it enters the column, and means permitting the withdrawal of the particles settling in said spigot outside of said chamber.
6. In a hydraulic classifier, the combination with a tank, of a sorting column through which the fluid ascends and in which separation of heavier from lighter particles occurs, of a spigot at the lower end of the sorting column and having an internal chamber, said chamber having an inlet, for water under pressure, and a member positioned between the lower end of the sorting column and the upper portion of said chamber having substantially spiral grooves inclined sharply to the horizontal for imparting a whirling action to the water at the point of discharge from the grooves.
7. In a hydraulic classifier, a sorting column through which the fluid ascends and in which separation of heavier from lighter particles occurs, a spigot at the lower end of the sorting column and having an internal chamber with an inlet thereto, for water under pressure, and means positioned between the lower end of the sorting column and the upper portion of said chamber and substantially closing the upper end of the latter and having inclined channels for imparting a whirling action to the water at the point of discharge from the channels, said spigot having double walls forming a space around the internal chamber and communicating at the top with the sorting column and receiving therefrom the separated heavier particles, said spigot having a discharge for said heavier particles.
8. In a hydraulic classifier, a sorting column adapted to connect with the lower portion of a tank, said sorting column having a member at its lower end provided with spaced walls and an internal chamber, means within and substantially closing the upper portion of said chamber having water channels inclined to the horizontal for imparting a whirling action to the fluid at the point of discharge from the channels, the space between the walls of said member communicating with the column and adapted to receive the heavier particles settling therefrom, said internal chamber having a fluid inlet, and said member having an outlet through which the heavier particles may be withdrawn.

In testimony whereof I affix my signature in presence of two witnesses.
